UNITED STATES PATENT OFFICE.

EDWARD LAAS, OF CHICAGO, ILLINOIS, ASSIGNOR, BY MESNE ASSIGNMENTS, TO OTTO R. BARNETT, OF CHICAGO, ILLINOIS.

ANTICREEPER.

1,227,804.

Specification of Letters Patent. Patented May 29, 1917.

Application filed May 19, 1916. Serial No. 98,488.

To all whom it may concern:

Be it known that I, EDWARD LAAS, a citizen of the United States, residing at Chicago, in the county of Cook and State of Illinois, have invented certain new and useful Improvements in Anticreepers, of which the following is a specification.

My invention relates to an anti-creeper, that is, to a device to check the tendency of railroad rails to creep longitudinally; and the principal object of the invention is to provide an anti-creeper, preferably a one-piece device, which will take a firm and reliable hold on the rail, which will be strong enough to withstand the very considerable stresses to which such a device is subjected when the rail starts to creep and which, furthermore, will be light in weight, inexpensive to manufacture and can be conveniently applied to the rail, and which may be removed therefrom if occasion require it. Preferably also my device when on the rail will have a grip thereon at all times, tending to increase under creeping strain.

Among the advantages of a one-piece anti-creeper are cheapness of manufacture, convenience in handling, and impossibility of erroneous assembling of parts. However, difficulties have been experienced in constructing a one-piece device which will maintain its hold on the rail as against various disturbing influences to which an anti-creeping device is necessarily subjected and especially when the device is not under creeping pressure. Among these influences are the vibration of the rail, its tendency to contract so as to draw the device out of contact with the tie which it abuts, the differences in expansion and contraction as between the rail and the anchor which occur because of temperature changes, and the tendency of the rail to re-act after being relieved from the forward or creeping stresses. There is also the likelihood of the position of the device on the rail being disturbed either accidentally or otherwise by persons working on the roadbed. My present invention provides an anti-creeping device capable of construction in one-piece, but not necessarily so, and so constructed that when once applied to the rail there is little or no chance of its hold thereon being loosened from any of the above causes.

Lightness in weight is also an important consideration in a device of this sort since

rail anchors are used in such large numbers and are transported over such considerable distances so that cost of material and freight rates form an important factor in the price paid by the railroads.

My invention consists in certain novel arrangements and constructions, to be herein-after described and claimed, whereby the above stated objects, and such other objects as will hereafter appear, are obtained.

My invention is illustrated, in certain preferred embodiments, in the accompanying drawings where—

Figure 1 is a plan view of an anti-creeper constructed in accordance with the invention shown as applied to a rail.

Fig. 2 is a side elevation of the device showing the rail in section.

Fig. 3 is a sectional view on line 3—3 of Fig. 2.

Fig. 4 is a view, in perspective, of the rail anchor shown in the preceding figures.

Fig. 5 is a view, similar to Fig. 2, illustrating a modification.

Fig. 6 is a view, in perspective, of the modified form of device.

Fig. 7 is a plan view illustrating another modification.

Fig. 8 is a side elevation of the same, and

Fig. 9 is a sectional view on line 9—9 of Fig. 8.

Like characters of reference designate like parts in the several figures of the drawings.

Referring to the drawings, A represents a railroad rail and B one of the cross ties on which the rail is laid.

Having reference particularly to Figs. 1 to 4 inclusive, the anti-creeper shown in these figures consists of a bar 10 of metal preferably steel, which is arranged edgewise of the rail and is formed at opposite ends with means for engaging the edges of the base flange of the rail. When the device is made in one-piece, as shown in these figures, one end of the bar 10 is bent around, as indicated at 11, to form a tie abutting member 12, the extremity 13 of which bears against or comes very close to the body portion of bar 10. The bent portion of the device is notched at 14, 15 to receive one side of the base flange of the rail. Preferably the lugs 16, 17, which bear upon the upper inclined surface of the base flange, are bent forwardly and backwardly as shown, so that when the device is moved angularly with respect to

the rail, one of these lugs will bite into the top of the rail base and increase the hold of the device on the rail. The other end of the bar is formed with an enlarged portion

5 18 providing an edge 19 adapted to engage with and bite into the opposite side of the base flange of the rail. The enlarged portion 18 of the device is preferably bent backwardly away from the tie B, providing what 10 might be termed a locking tongue, the end of which is notched as shown at 20 for engagement with the edge of the base flange of the rail.

The device is applied to the rail as follows: The end 18 is slipped under the rail 15 and the device is applied on the rail from the other side until a close engagement is obtained between the jaws provided with notches 14 and 15 and the base flange on 20 this side of the rail. This brings the edge 19 in line with the adjacent edge of the base flange and by lifting this end of the device and expanding or straightening out the locking tongue 18, the device may be 25 brought into operative position shown in Figs. 1 and 2 with the edge 19 biting into the base flange and the notched tongue 20 engaging the same. The tongue remains strained, to a certain extent, so that it exerts 30 a spring pressure against the rail which absorbs any looseness and effectually prevents the hold on the rail being materially diminished by vibration or the other disturbing influences above mentioned. The end 35 of the device provided with the tongue 18 stands away from the tie B. Hence any tendency of the rail to creep is self-checked by the cramping action of the device on the rail. This may be produced also by driving 40 the end toward the tie, the tongue serving to prevent reverse movement. Any initial creep causes the edge 19 to bite deeper into the rail. It also causes the oblique lug 16 to bear with greater force against the top of 45 the rail base on this side of the rail. The extremity 13 of the tie abutting flange forms a fulcrum for the bar 10. By providing the device with two spaced jaws at one end any tendency there might otherwise be for the 50 device to twist or rock on an axis transverse to the rail is effectually checked. In the form of the invention shown in Figs. 1 to 4 inclusive, the lug 16 provides the holding power at this end of the device. The principal function of lug 17 is to prevent the 55 tendency of the device to twist which has just been mentioned.

If desired, this result may be obtained by providing the other end of the device, that 60 is, the end having the tongue 18, with a lug or member adapted to bear against the top of the rail. This arrangement is shown in Figs. 5 and 6. In addition to the biting edge 19^a and tongue 18^a this end of the device is formed with a projection 21 having

an upwardly curved lug or member 22 which bears on the upper surface of the base flange.

In Figs. 7 to 9 inclusive, I have shown a device in which the spring action, obtained primarily in the forms of the invention just described by straining the tongue 18 or 18^a, as the case may be, is brought about by straining the bar which extends under the rail base as well as the tongue. The bar 10^b has, as the device is originally constructed, an oblique relation with the rail engaging means at opposite ends thereof which latter may be the same as the corresponding rail engaging means shown in Figs. 1 to 4 inclusive, and are correspondingly numbered except that preferably the notch 20^b is tapered or beveled to increase the holding power of the tongue 18^b.

Fig. 7 shows the manner in which the device is applied to a rail. The tie abutting end is first driven onto the rail as far as it will go. This does not bring the edge 19^b in line with the edge of the base flange of the rail. It stands a trifle inwardly of the edge of the base flange. The bar 10^b, it will be understood, is oblique with respect to the rail. The tie abutting end of the device is held against the tie by any suitable means and the other end is drawn backwardly 95 away from the tie until the biting edge 19^b is brought out as far as the edge of the base flange. At the same time, by a suitable tool, the tongue 18^b is straightened out or expanded and this end of the device raised to bring the notch 20^b to the level of the base flange. This position of the parts is indicated by the dotted line figure marked 10^b. When released the device will assume the other position indicated in Fig. 7 in which 105 position it takes a hold on the rail, the firmness and reliability of which is increased by the fact that the bar 10^b is under strain as well as the hook 18^b.

While I have described my invention in certain preferred embodiments, it will be understood that further modifications might be made without departure from the principles of the invention. Therefore I do not wish to be understood as limiting the invention to a one-piece device or to any of the typical embodiments shown and described except so far as such limitations are expressed in certain of the claims.

I claim:

1. An anti-creeper provided with a tie abutting part and at one end with a pair of spaced rail engaging jaws and at the other with a locking tongue extending backwardly away from the tie which, when the 125 device is in place, bears with spring action against the rail.

2. An anti-creeper provided with a tie abutting part and at one end with a pair of spaced rail engaging jaws and at the other 130

with a locking tongue notched for engagement with the rail base extending backwardly away from the tie which, when the device is in place, bears with spring action 5 against the rail.

3. A one-piece anti-creeper provided at one end with a pair of spaced rail engaging jaws and at the other with a flexible locking tongue which, when the device is in place, 10 bears with spring action against the rail.

4. A one-piece anti-creeper provided with a tie abutting part and at one end with a pair of spaced rail engaging jaws, and at the other with a locking tongue extending 15 backwardly away from the tie which, when the device is in place, bears with spring action against the rail.

5. A one-piece anti-creeper provided with a tie abutting part and at one end with a 20 pair of spaced rail engaging jaws and at the other with a locking tongue notched for engagement with the rail base extending backwardly away from the tie which, when the device is in place, bears with spring action 25 against the rail.

6. A one-piece anti-creeper, a portion of which is flexible and is strained by application of the device to a rail, one end of said device being bent to form a tie abutting 30 part with its extremity bent back to stand close to the body of the device.

7. A one-piece anti-creeper, a portion of which is flexible and is strained by application of the device to a rail, said device being formed at one end with two spaced lugs bearing against the upper face of the rail 35 base.

8. A one-piece anti-creeper, a portion of which is flexible and is strained by application of the device to a rail, said device being formed at one end with two spaced lugs bearing against the upper face of the rail base, and one of said lugs being oblique 40 to the rail.

45 9. A one-piece anti-creeper, a portion of which is flexible and is strained by application of the device to a rail, said device being formed at one end with a tie abutting part and with a diagonally disposed lug bearing on the upper surface of the rail base, and at the other with an edge bearing 50 against the edge of the rail base and with a rearwardly projecting part notched for engagement with the rail base.

55 10. A one-piece anti-creeper, a portion of which is flexible and is strained by application of the device to a rail, said device being formed at one end with a tie abutting part and with a diagonally disposed lug 60 bearing on the upper surface of the rail base, and at the other with an edge bearing against the edge of the rail base and with a rearwardly projecting part notched for engagement with the rail base, one end of 65 the device being provided with an addi-

tional member which bears against the upper surface of the rail base, for the purpose described.

11. A one-piece anti-creeper, a portion of which is flexible and is strained by application of the device to a rail, one end of said device being bent over to form a tie abutting member and notched to provide two spaced rail base engaging jaws, the other end of the device being formed with an edge 70 adapted to bear against the edge of the rail base, and a rearwardly projecting notched locking tongue.

12. An anti-creeper consisting of a flat strip of metal arranged edgewise of the rail 80 with an enlargement at each end, the enlargement at one end being bent over to form a tie abutting member and notched to provide rail engaging means, the enlargement at the other end being bent in 85 the opposite direction and formed to engage the edge of the rail base at two points lengthwise of the same.

13. An anti-creeper consisting of a flat strip of metal arranged edgewise of the rail 90 base and formed with an enlargement at each end, the enlargement at one end being bent over with its extremity close to the body of the device to provide a tie abutting member and being formed with two obliquely disposed lugs adapted to bear 95 against the upper surface of the rail base, the enlargement at the other end of the device being bent in the opposite direction and formed to provide an edge adapted to bear 100 against the edge of the rail base, and a notched locking tongue to engage the rail base at a point more remote from the tie than the point against which said edge bears.

105 14. An anti-creeper consisting of a flat strip of metal arranged edgewise of the rail base and formed with an enlargement at each end, the enlargement at one end being bent over with its extremity close to the 110 body of the device to provide a tie abutting member and being formed with two obliquely disposed lugs adapted to bear against the upper surface of the rail base, the enlargement at the other end of the device being bent in the opposite direction and formed to provide an edge adapted to bear 115 against the edge of the rail base, and a notched locking tongue to engage the rail base at a point more remote from the tie 120 than the point against which said edge bears, the end of the device provided with said tongue being formed also with a member extending around and bearing upon the top of the base flange of the rail.

125 15. An anti-creeper consisting of a flat strip of metal arranged edgewise of the rail base, adapted to be strained when applied to the rail, and formed with an enlargement at each end, the enlargement at one 130

end being bent over with its extremity close to the body of the device to provide a tie abutting member and being formed with two obliquely disposed lugs adapted to bear 5 against the upper surface of the rail base, the enlargement at the other end of the device being bent in the opposite direction and formed to provide an edge adapted to bear against the edge of the rail base, and a 10 notched locking tongue to engage the rail base at a point more remote from the tie than the point against which said edge bears, the end of the device provided with said tongue being formed also with a member extending around and bearing upon the top of the base flange of the rail.

16. A one-piece anti-creeper consisting of a bar of steel, one extremity of which is

bent over in the direction toward the tie to form a bearing for the device against the tie, the other end being bent in the opposite direction to provide a spring locking hook the extremity of which is notched and engages the rail base at a point more remote from the tie than the body portion of 25 the bar.

17. A one-piece anti-creeper consisting of a bar of steel, one extremity of which is bent over in the direction toward the tie and is notched to form two tie engaging 30 jaws, the other end being bent in the opposite direction and notched at its extremity to form a spring locking hook adapted to engage the base flange of the rail.

EDWARD LAAS.
